US0D1085170S

(12) **United States Design Patent** (10) **Patent No.:** **US D1,085,170 S**
(45) **Date of Patent:** **** Jul. 22, 2025**

(54) **SCREED COMPONENT**

(71) Applicant: **CATERPILLAR PAVING PRODUCTS INC.**, Brooklyn Park, MN (US)

(72) Inventors: **Michael S. Hemry**, Maple Grove, MN (US); **John E. Jorgensen**, Andover, MN (US); **Monica Agnieszka Orfei**, North St. Paul, MN (US); **Cameron E. Graves**, Summerset, SD (US); **Dustin W. Bryan**, Blaine, MN (US)

(73) Assignee: **CATERPILLAR PAVING PRODUCTS INC.**, Brooklyn Park, MN (US)

(**) Term: **15 Years**

(21) Appl. No.: **29/909,858**

(22) Filed: **Aug. 11, 2023**

Related U.S. Application Data

(63) Continuation of application No. 29/865,931, filed on Aug. 22, 2022, now Pat. No. Des. 1,001,161, which (Continued)

(57) **CLAIM**

The ornamental design for a screed component, as shown and described.

DESCRIPTION

FIG. 1 is a front, top, left perspective view of a screed component showing the new design;

FIG. 2 is a rear, bottom, right perspective view thereof;

FIG. 3 is front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a front, top, left perspective view thereof in an environment of use.

The broken lines show portions of the screed component that form no part of the claimed design. The broken lines seen in FIG. 9 are for the purpose of showing environmental structure, and form no part of the claimed design.

1 Claim, 9 Drawing Sheets

Related U.S. Application Data

is a continuation of application No. 29/721,904, filed on Jan. 24, 2020, now Pat. No. Des. 971,968.

(58) Field of Classification Search

CPC E01C 19/00; E01C 19/48; E01C 19/4873

See application file for complete search history.
